CLAIM

The ornamental design for a steering wheel, as shown and described.

DESCRIPTION

FIG. 1 is a front perspective view of a steering wheel showing our new design;

FIG. 2 is a top perspective view thereof;

FIG. 3 is a side view thereof; and,

FIG. 4 is a rear view thereof.

It will be understood that the broken lines shown in the drawings illustrate portions of the steering wheel that form no part of claimed design.
